UNITED STATES PATENT OFFICE.

EDWARD J. McEVoy, OF NEW YORK, N. Y., ASSIGNOR OF ONE-HALF TO THE WILLIAM CRAMP & SONS SHIP AND ENGINE BUILDING COMPANY, OF PHILADELPHIA, PENNSYLVANIA.

DESIGN FOR A GLOBE-HOLDER.

SPECIFICATION forming part of Design No. 22,227, dated February 21, 1893.

Application filed January 3, 1893. Serial No. 457,143. Term of patent 14 years.

To all whom it may concern:

Be it known that I, EDWARD J. McEVoy, a citizen of the United States, residing in the city, county, and State of New York, have invented and produced a new and original Design for a Socket or Holder for Incandescent Electric Lights or for Lamps or other Lighting Devices, of which the following is a specification, reference being also had to the accompanying drawings, in which—

Figure 1 is a view in perspective of a holder embodying my design, and Fig. 2 a side elevation of the same, the two views being deemed necessary to fully illustrate the design.

The leading feature of my design consists in a holder the basal portion of which, or that portion which is designed to be applied and affixed to the wall or other supporting device, is a parallelopipedon, and, therefore, in side elevation, rectangular;—while the socket portion, or that portion with relation to which the lamp or light is applied and connected,

is conical in general contour, presenting a tapering appearance from whatever point of view it may be observed, and truncated, the conical effect being produced by a series of gradually diminishing curved portions, or cylindroform or curvilinear members b, b', b^2, b^3 , so to speak, which together however constitute what is, in effect, a truncated conical body.

In the drawings, A designates the quadrangular basal portion of the holder, and B the conical socket portion of said holder.

Having thus described my invention, I claim—

The design for a globe holder, substantially as herein shown and described.

In testimony that I claim the foregoing as my invention I have hereunto signed my name this 21st day of December, A. D. 1892.

EDWARD J. McEVoy.

In presence of—

J. BONSALL TAYLOR,
Wm. C. STRAWBRIDGE.
